UNITED STATES PATENT OFFICE.

MICHAEL CARTER, JR., OF CHICAGO, ILLINOIS, ASSIGNOR OF ONE-HALF TO
CHARLES T. BROWN, OF SAME PLACE.

DRAFT APPARATUS FOR CARS.

SPECIFICATION forming part of Letters Patent No. 451,851, dated May 5, 1891.

Application filed December 11, 1890. Serial No. 374,406. (No model.)

To all whom it may concern:

Be it known that I, MICHAEL CARTER, Jr., a citizen of the United States, residing at Chicago, in the county of Cook and State of Illinois, have invented certain new and useful Improvements in Draft Apparatus for Rail-way-Cars, of which the following is a full and complete description.

My invention relates to that class of draft

apparatuses wherein the tension upon the draw-head of the car caused by the hauling of the train shall be transmitted through the draft apparatus of each car without direct strain on the timbers and frame-work of the car other than that required to haul such car and its contents. In other words, in cars fitted with draft apparatus of the character of this the timbers and frame-work of the car do not receive the strain of the cars behind such car in the hauling of the train, such strain being borne by the draft apparatus. Draft apparatuses of this character are usually known among railroad-men as "continuous draft-rods."

The object of my invention is to obtain a draft apparatus wherein a continuous rod is dispensed with, but the results attained by using a continuous rod are secured, and a draft-rod apparatus in which the several parts entering as elements into its construction shall also so enter into the construction of the car that the car will be strengthened thereby, as well as relieved of the strain of the cars in the train to the rear of the car to which my device is attached, the draft apparatus being adapted to receive such strain.

I have illustrated my invention by the drawings accompanying and forming a part hereof, in which—

Figure 1 is an end view of a flat car-body having my invention placed thereon; Fig. 2, a bottom plan view of a portion of a car-body having the device secured thereon; Fig. 3, a longitudinal section of a car-body having my device secured thereon; Fig. 4, a cross-section on line 4 4 of Fig. 2, viewed in the direction of the arrow. Fig. 5 is a perspective view of an end plate adapted to be secured to the end of the draft-timbers of the car to protect such draft-timbers from being battered by the com-

ing into contact of any two cars. Fig. 6 is a perspective view of a follower-plate required in the construction of a draft-rod apparatus embodying my invention.

Like letters refer to like parts throughout the several views.

A are the car-sills.

A' are the cross-timbers at the end of the car-body.

A² A² are cross-timbers underneath the car-body.

a is the floor of the car-body.

B is the draw-head.

b is the yoke of the draw-head B.

C is a carrying-iron and brace.

C' is a buffer-timber.

C² C² are rods extending through the buffer-timber downward on each side of the draft-iron to and through the carrying-iron and brace C.

D D are draft-timbers.

d d are grooves in draft-timbers D D.

E E are draft-rods.

E' is a draft-rod.

F F' are followers.

f f' are respectively turned-up edges forming flanges on the followers F F'.

f³ are holes in the followers F F', through which holes the draft-rods E E are passed, fitting loosely, so that the followers may move 80 upon the rods. The draft-rods E are set into the grooves d, cut in the draft-timbers D D, so as to be supported thereby, and also to allow the draft-timbers to be placed closely up against the yoke b of the draw-head B.

G is the transom of the car-body, and g the hole therein for the king-bolt extending into the truck of the car.

H is an end plate fitting over the end of timbers D D, respectively, forming a shoe, 90 against which end plate the follower F' is forced when two or more cars are brought together.

h is a slot through the flange and body of the plate H, and this flange h corresponds in 95 location with the groove d, so that when the plate H is put in proper position on the end of the draft-timber D the draft-rod E may be laid therein and in the groove d.

h' h' are flanges on plate H.

70

75

80

85

100

H' are plates fitting over the cross-timbers A² A², through which plates the several draft-
rods pass.

H² is a plate placed against the timber A²,
5 against which plate the nut h² or its equivalent on draft-rod E' is firmly secured.

h³ is a hole through which a bolt securing
the shoe H to the timber can pass.

I is a spring placed between the followers
10 F F', and such followers pass through the yoke
b of the draft-iron B.

J is a tie-iron extending from one of the
draft-timbers D to the other thereof, preventing
them from spreading.

15 The inner end of the draft-head B is sup-
ported by the followers F F', as can be
seen by inspection of the drawings, Fig.
3, the followers being supported by being
threaded on the draft-rods E E. The draft-
20 timbers D are secured firmly in the ordinary
manner to the timbers A, but are cut off at
the ends thereof, so that follower F', being the
inner follower of the two required, abuts or
presses against the timber (or against the plate
25 placed over the timber to protect it) in coup-
ling cars or whenever from any cause any
two cars run together. The draft-rods E have
nuts e thereon or locking-pins e', as preferred,
holding them in place. Each of the four draft-
30 rods E E required in the draft apparatus
of a car having my device placed thereunder
extends through the front followers F, (one
of such followers being placed at each end of
the car,) through the rear follower F', along
35 the groove d in draft-timber D, through the
cross-timber A² and the plate H', and over the
transom G. The dotted line K is substantially
the center line of the car from each end there-
of. The rod E' extends through the plate H',
40 through plate H², and through the timbers A²
A², and is secured firmly in position by nuts
h² or other equivalent device.

The operation of the device is, if tension be
exerted on draw-head B, such draw-head is
45 drawn forward, carrying with it follower F'
inside of the yoke b at the inner end of the
draw-head and against the spring I, forcing
the forward end of such spring against the
follower F, and the follower F not being al-
50 lowed to go forward on account of the nut e
or other equivalent device placed thereon the
spring is compressed, the amount of such com-
pression varying with the number of cars
back of the car to which the device is attached
55 and the grade over which the train is passing
or from any sufficient cause. Draft-rods E E are
immovable; but the tension produced
therein by the forcing of the follower F against
the nuts thereon is transmitted through the
60 rods E E, thereby bringing the pin e', or other
equivalent stop at the inner end of the rods
D, firmly against the plate H' on timber A²,
and the plate H² upon the other side of the
cross-timber A² being held firmly against such
65 cross-timber A² by the nut h² on the outer end
of rod E' such strain is transmitted to the rod
E', and, through elements consisting of the

rods E E and followers F F' inclosed within
the yoke b of the draw-head B at the other
end of the car, and duplicates of the parts at
70 the end of the car described and illustrated,
to the other draw-head. When the cars are
brought forcibly together, as in coupling,
the draw-head B is pushed inwardly, thereby
forcing inward the follower F against 75
the spring I, the other end of the spring be-
ing thereby forced against the other fol-
lower F', and such follower thereby pushed
against the plates H on the end of the draft-
timbers D D. The timbers D D therefore re-
ceive the buffing strain in the contact of two
or more cars, and such timbers extend under
the car from the shoes H H to a point equi-
distant from the other end of the car, where
a like shoe H is placed to receive the buffing 85
strain from the other draw-bar when such
other draw-bar is pushed in by contact with
another car in case of a car being linked or
coupled. The plates H' H² and the cross-
timber A², being firmly pressed together and 90
secured by the nut h² on draft-rod E' and
pins e' e' or equivalent fastening on draft-
rods E E, constitute a transverse bar, through
which the several draft-rods named pass and
from which they cannot be withdrawn be- 95
cause of these fastenings h² e'.

Having thus described my invention, what
I claim, and desire to secure by Letters Pat-
ent of the United States, is—

1. The combination of a draw-head pro-
vided with a yoke on the inner end of the
stem thereof, draft-rods extending on each
side of the yoke to and through a transverse
bar at the other end of such rods and secured
therein, a front and a rear follower extend-
ing through the yoke on the draw-head and
supported by but moving freely on the draft-
rods, the forward one of the followers abut-
ting against a stop on the draft-rods and the
rear one thereof abutting against draft-tim-
bers secured to the body of the car, a spring
100 placed within the yoke and between the fol-
lowers, a tension-rod extending through and
secured in the transverse bar and through
and secured in a second and like transverse
105 bar at the other end thereof, and draft-rods
attached to such second transverse bar and
extending to and by the side of the yoke of a
draw-head at the other end of the car and
having followers thereon, with a spring inter-
110 posed between them and within such yoke in
the same manner as the first-named followers
and spring are placed upon the first-named
draft-rods, substantially as described.

2. The combination of a draw-head pro-
vided with a yoke on the inner end of the
stem thereof, draft-timbers having a groove
therein, in which are placed draft-rods ex-
tending by the side of the yoke of the draw-
head, followers supported by and moving
120 loosely on the draft-rods, such followers hav-
ing a horizontal flange thereon and the for-
ward one thereof abutting against the stop
on the draft-rods and the rear one abutting

against the draft-timbers, a spring interposed between the followers within the yoke, transverse bars through which the draft-rods pass and in which they are secured, a tension-rod 5 passing through and secured in the transverse bar and through a second transverse bar, and other draft-rods passing through and secured in the second transverse bar, such last-named draft-rods extending to and by 10 the side of the yoke of the draw-head at the

other end of the car and through other followers placed thereon passing through the yoke of such other draw-head, such last-named followers having a spring interposed between them within such yoke, substantially 15 as described.
